UNITED STATES PATENT OFFICE.

FREDERICK E. COMSTOCK, OF VALPARAISO, INDIANA, ASSIGNEE OF ONE-HALF TO
GEORGE LA FORCE, OF VALPARAISO, INDIANA.

MECHANICAL SHOE FORM.

Application filed March 2, 1922. Serial No. 540,424.

To all whom it may concern:

Be it known that I, FREDERICK E. COMSTOCK, a citizen of the United States, residing at Valparaiso, in the county of Porter and State of Indiana, have invented certain new and useful Improvements in Mechanical Shoe Forms, of which the following is a specification.

My invention relates to improvements in mechanical shoe forms and it more especially comprises the features pointed out in the annexed claims.

The purpose of my invention is to provide a mechanical shoe form that shall combine the advantages of pneumatically controlled forms with the added advantage of specifically controlling the pressure within the shoe at the points most desired; that retains the shape of each manufacturer's style of shoes instead of destroying the same and bringing the shape of all shoes to one common standard; that provides adjustable means for holding the shoe distended under definite controllable conditions; and that may be applied to existing forms of lasts whether these represent individual or manufacturer's shapes.

With these and other ends in view, I illustrate in the accompanying drawing such instances of adaptation as will disclose the broad underlying features without limiting myself to the specific details shown thereon and described herein.

Figure 1 illustrates a side elevation of a shoe form in assembled relation, partly in section.

Figure 2, is a top plan view of the form with parts broken out showing the interior construction.

Even though the form is shown in connection with a right hand low shoe, it is equally adaptable to left hand lasts and also to high shoes. In the latter case any of the available expedients shown in my co-pending applications, Serial Nos. 439,600½, filed January 24, 1921, and 498,356, filed September 3, 1921, or any other expedient may be used to hold the top distended.

The shoe 1 has enclosed therein the last 2 which may be of wood, metal, etc., as exemplified it is of wood construction. It has a forward extension 6 that projects beneath the shoe toe 3 and it has a recess 7 formed on its under side in which the pressure adjusting means are located. The two points

of a shoe at which pressure should be applied in order to retain the best shape of the upper, is at the inner heel position 4 and the inner sole position of the toe portion of the shoe at 5. If the last projection 6 can be pressed upward, then the shoe part 3 will take the shape of the last whatever variation there may be between lasts.

This desirable result is produced by means of a pressure tongue 8 located within the recess 7 where it is fulcrumed on pin 11. The forward end 9 presses against the inner sole 5, when the rear end 10 is drawn upward by the adjusting screw 16 causing the pressure tongue to move on its fulcrum 11, so as to lift the last projection 6 at the same time that the forward end 9 of the tongue is moving downwardly against the inner sole. In this way the shoe upper is distended the required amount at the most desired place, thus retaining the outer shape of the shoe to conform to the contour of the last.

This desirable feature is attained by simply turning the thumb screw 18, by reason of the fact that its stem 16 is threaded at the lower end into a pivoted nut 14, to which the flange sides 12 of the pressure tongue 8 are pivoted on reduced ends 15. The screw 16 at its upper end bears on washer 17, and the extreme upper end above the knurled head 18 has a slight screw slotted projection. The hole through the last to accommodate screw 16 may be enlarged at the bottom end sufficient to allow lateral movement of the screw as the rear end of the pressure tongue is moved up or down causing the pivoted nut 14 to, in its short travel, describe an arc whose center is in the fulcrum pin 11. The pressure tongue is formed with sides 12 to somewhat simulate a trough or channel in cross section, the web or base having the side flanges bent upward. At the time that this bending is done, the pivot nut 14 may be assembled with its reduced ends 15 entering the flanges 12. On the under side of the nut 14, a clearance hole is formed to accommodate the projecting end of the screw 16.

In order that upward pressure may be applied at the heel of the last, I may provide the following means or any substantial equivalent thereof. Pressure applied at 4 by the plate 22 will force the rear portion of the last against the upper at about 26,

and thus hold the last firmly in place. This is accomplished in the case of a wooden last by inserting a bearing tube 20 in the last, and passing through this an adjusting screw 19. The lower end of the screw is threaded at 21 for engagement with threads in the lower end of the sleeve 20. It is turned by means of the knurled thumb nut 27 attached to its upper end. This nut also has a slotted projection similar to thumb nut 18 so that when desired a screw driver may be used. The screw 19 bears against the heel pressure plate 22 moving the plate downward as required against the heel portion 4, while the plate is pivoted on pin 24 passing through the ears 23. A suitable slot 25 may be cut in the bottom of the heel portion of the last to accommodate the ears of the pressure plate 22. The pressure tongue 8 may be held approximately central of the last transverse of the recess 7, on pin 11 by means of distance collars 13 which expedient, as well as the use of pivoted nut 14 and the heel pressure expedient, may be varied as desired.

It will be seen that the invention is very effective in applying controlled pressure to whatever parts of the shoe are to be emphasized for display purposes, being made in right and left hand shapes according to special makers' styles. The device is simple to operate, economical in manufacture and rapidly applied.

It is understood that the shoe will be laced over the last as though it were on the wearer's foot. Also that the pressure tongue may be more or less elastic so as not to overstress the shoe upper when the last is being adjusted.

If desired, the knurled thumb screws 18 and 27 may be substituted by wing nuts, or they may have ordinary slotted ends which are buried in suitable recesses formed around the screws within the last top so as not to be visible. It is understood that I do not limit myself to the relation shown of the fulcrum 11 and the adjusting screw 16, as these, under certain circumstances, may be transposed. To make it easy to insert the form into high shoes, I may slot the toe portion 6 at 27, shown at A Fig. 2, so as to let the tongue pass into the slot as the form is inserted into the shoe.

What I claim is:

1. In shoe forms, a specially shaped single piece last having a recess formed on the under side lengthwise thereof, a movable tongue extending from the toe portion of the last to near the heel portion thereof, said tongue being pivoted to the side walls of the recess, a threaded member pivoted to

the tongue near its rear end, adjusting means cooperating with the last and the threaded member adapted to move the rear end of the tongue upward and simultaneously move the front end of the tongue downward against the shoe sole so as to move the toe portion of the last upward and thus press the last against the front of the shoe upper. 70

2. In shoe forms, a single piece unitary removable last having a recess formed lengthwise thereof on its under side, a tongue pivoted to the side walls of the recess so that its forward end projects below 75 said walls and the rear portion of the tongue terminating within the recess and above the lower contour of the last, and means positioned in the last adapted to raise and lower the rear end of the tongue 80 so as to move the toe portion of the last toward or from the shoe upper.

3. In shoe forms, a single piece unitary removable last having a recess formed lengthwise thereof on its under side, a 85 tongue pivoted to the side walls of the recess so that its forward end projects below said walls and the rear portion of the tongue terminating within the recess and above the lower contour of the last, means positioned 90 in the last adapted to raise and lower the rear end of the tongue so as to move the toe portion of the last toward or from the shoe upper, separate pivoted means placed below the heel portion of the last, and means for 95 moving said means against the inner surface of the shoe heel to thereby raise the last against the shoe counter.

4. In shoe forms, an individually shaped last having a lengthwise channel formed 100 on its under side, a tongue pivoted in the channel so that its front end is movable away from the last and the rear end is simultaneously movable toward the last within the channel, and means for thus positively moving the tongue to cause the forward end of the last to press against the upper. 105

5. In shoe forms, a unitary last having a lengthwise channel formed on its under side 110 extending approximately from the heel to the toe, a tongue pivoted for movement within the channel, a separate plate pivoted at the heel portion of the last, independent adjusting means for the tongue and the plate adapted to directly press the plate and the forward end of the tongue against the inside of the shoe sole. 115

In testimony whereof I affix my signature.

FREDERICK E. COMSTOCK.
